(57) **CLAIM**

The ornamental design for a multi-block PCR thermal cycler device, as shown and described.

DESCRIPTION

FIG. 1 is a front, top and side perspective view of an multi-block PCR thermal cycler device, according to a first exemplary embodiment;

FIG. 2 is a front view of the multi-block PCR thermal cycler device of FIG. 1;

FIG. 3 is a back view of the multi-block PCR thermal cycler device of FIG. 1;

FIG. 4 is a right side view of the multi-block PCR thermal cycler device of FIG. 1;

FIG. 5 is a left side view of the multi-block PCR thermal cycler device of FIG. 1;

FIG. 6 is a top view of the multi-block PCR thermal cycler device of FIG. 1;

FIG. 7 is a bottom view of the multi-block PCR thermal cycler device of FIG. 1;

FIG. 8 is a front, top and side perspective view of an multi-block PCR thermal cycler device, according to a second exemplary embodiment;

FIG. 9 is a front view of the multi-block PCR thermal cycler device of FIG. 8;

FIG. 10 is a back view of the multi-block PCR thermal cycler device of FIG. 8;

FIG. 11 is a right side view of the multi-block PCR thermal cycler device of FIG. 8;

FIG. 12 is a left side view of the multi-block PCR thermal cycler device of FIG. 8;

FIG. 13 is a top view of the multi-block PCR thermal cycler device of FIG. 8; and,

FIG. 14 is a bottom view of the multi-block PCR thermal cycler device of FIG. 8.

The broken lines shown in the figures are included for the purpose of illustrating portions of the multi-block PCR thermal cycler device and form no part of the claimed design.
